PROTECTION OF WELLS

Thomas O. Allen, Bellaire, and John C. McDuffie, Jr., and John O. Minter, Thompsons, Tex., assignors, by mesne assignments, to Jersey Production Research Company

Application December 24, 1956, Serial No. 630,312

11 Claims. (Cl. 166—22)

The present invention is directed to a method for protection of wells. More particularly the invention is concerned with the placement of a protective fluid in an exposed area in a well bore. In its more specific aspects, the invention is concerned with the protection of perforations in a well casing following which an operation is performed in the well.

The present invention may be briefly described as a method for protecting an exposed area or perforations in a well having tubing arranged therein or in a well casing with the lower open end of the tubing maintained at a level a substantial distance above the exposed area or the perforations in the well casing. In the present invention the well has penetrated a hydrocarbon producing interval or zone and the well is filled with well fluids such as oil, gas and water from the productive zone, strata, interval, horizon, sand, formation, and the like. In the practice of the present invention the tubing maintained at the particular level has introduced into it at the well head a low fluid loss emulsion or gel which has the property of forming a cohesive body. The emulsion is flowed out of the lower end of the tubing to form the cohesive body in and to fill the area and to extend in an elongated form from the lower end of the tubing through the well fluids, separate and distinct from the well fluids, to the area to be protected. The introduction of the emulsion or gel is discontinued and the well fluids are displaced from the well up the annular space between the tubing and the wall of the well. The cohesive body remains in and protects the exposed area during the displacement of the well fluids while the tubing is maintained with its lower end at the level. It is contemplated that the tubing will be maintained in place in the practice of the present invention with its lower open end at a level from about 50 to 1000 feet above the exposed area or zone which is to be protected. Thus, the fluids employed for protection form a continuous and cohesive body without discontinuities in the placement thereof and flow downwardly as if directed in a confining channel such as a pipe or tubing. This is a valuable property of the protective fluids since it allows and contributes to the obtaining of the advantages of this invention.

The emulsion or gel is suitably placed in the tubing at the well head and then pumped downwardly by a workover fluid free of gas, following which the fluid free of gas may be employed to displace the well fluids from the annular space in the well. Subsequent to the displacement of the well fluids from the well, operations may be performed in the well or well casing such as repairing leaking tubings and the like. For example, a leaking tubing may then be removed from the well, repaired or replaced with a tube free of leaks following which the cohesive body is removed from the area by providing a pressure differential into the well bore which causes the cohesive body to be flowed from the protected area or interval of the casing and from the well. There-

2

after, hydrocarbons are again produced from the area which was protected in the well bore.

The low fluid loss fluid, gel, or emulsion employed in the practice of the present invention may suitably be a fluid such as an emulsion of an oily phase and a water phase and the like. Suitable materials have been amply described in Serial No. 567,604, filed February 24, 1956, for Bryan E. Morgan and Gerald G. Priest. The fluids described in Serial No. 567,604 are eminently suitable 5 in the practice of the present invention and comprise a stable emulsion of an oily medium and an aqueous medium which has a controllable density, the density of the emulsion being adjusted by dissolving a weighting agent in one of the phases of the emulsion to produce a 10 solids-free emulsion. Other suitable protective fluids are described in pending application Serial No. 630,266, filed December 24, 1956, for Gerald G. Priest, Bryan E. Morgan and Bertie F. Birdwell, in which an emulsion of an oily phase and an aqueous phase is described and 15 claimed, the emulsion in Serial No. 630,266 being a stable emulsion employing as an emulsifying agent a water-soluble salt of purified lignin sulfonic acid or a water-soluble salt of lignin sulfonic acid containing a certain amount of ash and reducing sugars. Other fluids 20 suitable in the practice of the present invention are described in Serial No. 630,026, entitled "Well Completion Fluids," and filed December 24, 1956, for Gerald G. Priest, Bryan E. Morgan, Melba L. Lytle, Bertie F. Birdwell and Joseph A. Caldwell. In Serial No. 630,026 a 25 heat stable, non-corrosive emulsion is described and claimed in which an emulsifying agent is employed and in which the oily phase of the emulsion comprises a substantial amount of tetrachloroethylene, with one of the 30 phases of the emulsion containing a corrosion inhibitor. These several low filtration loss fluids described in the several applications have the characteristic of low filtration rate and further the characteristic of maintaining perforations open and exposed areas in wells protected without damaging or injuring the permeability and 35 porosity of the formation or interval with which they come into contact. In short, the low fluid loss fluids suitable for use in the present invention have the characteristic of low filtration rate and of resisting entrance of other fluids into perforations in or into an earth formation. 40 In addition, these fluids, particularly those described in the several applications, do not damage a formation or sand and the like with which they come into contact. These low fluid loss fluids, gels, or emulsions have the further property of forming a cohesive mass 45 which does not readily substantially intermingle or mix with other fluids such as well fluids as exemplified by oil, gas, water and the like. The fluids or emulsions employed suitably have a low fluid loss, a weight at least equal to that of the normal working fluids employed for 50 blowout protection in wells and are free of constituents which might permanently plug the formation or casing perforations. Thus, the fluids used in the practice of this invention block ingress of damaging fluids from the well to the formation but allow fluids from the formation to flow into the well bore on adjustment of the differential pressure into the well bore. 55 In the present invention a method is provided for protecting a productive zone in a well without lowering the tubing to the productive zone and without running a 60 tubing extension which would effectively extend the tubing to the producing zone. The advantage and utility of placing a protective fluid or emulsion in an exposed zone or area without lowering the effective depth of the tubing lies in the fact that the work is performed before removing the Christmas tree from the well head and installing the blowout preventers. This provides protection 65 from blowouts which might occur while lowering the 70

tubing prior to circulating the well. Furthermore, the present invention saves operational time and expense as compared with the use of a tubing extension to increase the effective depth of the tubing. In each instance the placement of the protective fluid in the area or zone to be protected prior to filling and circulating the well with the usual working fluid for blowout protection has the advantages of (a) where salt water is used as a working fluid, the fluid prevents loss of salt water to the formation during the circulating operation, and (b) in the case of the use of mud as the working fluid, preventing the mud from contacting the exposed productive horizon which would tend to plug the formation material in the horizon and reduce its subsequent productivity. Furthermore, by using the protective fluid subsequent cementing or sand control operations in the protected area are facilitated and make possible effective treatment in such operations.

In the practice of the present invention, a protective fluid of the type illustrated before is introduced or pumped into the tubing in a small quantity, which may range from about 1 to about 20 barrels and may be followed by pumping the usual workover or well servicing fluid to displace the protective fluid out of the bottom of the tubing. By using a protective fluid heavier than the well fluids in the well bore prior to conducting a well servicing or well workover operation, the well fluids in the well bore below the bottom of the tubing may be displaced into the zone open to production by the differential weight of the protective fluid. Thus, the protective fluid, which has the property of forming a cohesive body, settles to the area in the producing zone without intermingling or mixing with the well fluids. The protective fluids have the characteristic of a low filtration or fluid loss and do not enter the formation following the well fluids. On opening the casing-tubing annulus connection at the well head, the well fluids in the annulus are circulated or displaced back to the surface as they are displaced by pumping of the servicing or workover fluids into the tubing. In this manner, oil and gas in the annular space are removed and the well bore above the protective fluid is completely filled with the working fluid for blowout protection during subsequent operations.

The working fluid is suitably oil, salt water, which may contain a weighting agent, or drilling fluids such as drilling mud, or the like. The important consideration of using the protective fluid in the manner indicated is that the exposed area of the perforations is not contacted with the workover fluid. In addition, the employment of the protective fluid in the manner indicated has other advantages, among which is its property of forming and remaining in a cohesive mass. This is an important consideration since many well servicing or work-over operations are occasioned or caused by the presence of leaks in the tubing such as actual holes in or around the threads of the couplings. In view of the protective fluid having its property of cohesiveness by virtue of its viscosity and gel strength and differential weight advantage, it does not flow out of small holes in the tubing and substantially by-passes small holes or leaks in the tubing as a slug or body. Furthermore, it is not circulated back to the surface from the level at which a leak may occur and it does not circulate up the annular space between the tubing and the wall of the well or casing. Additionally, by virtue of a differential pressure between the tubing and the casing-tubing annulus the protective fluid may suitably fill any openings or leaks in a tubing intermediate the ends of the tubing and allow subsequent circulation of work-over fluids without being by-passed through the leaks.

After a workover operation has been employed in a well in accordance with the present invention, the workover fluid may be replaced by lighter fluid, such as fresh water which lightens the column in the well and provides a pressure differential into the well bore which will cause

5 differential pressure to displace the cohesive body from the protected area and up the repaired tubing, for example, following which production of valuable hydrocarbon fluids from the well is obtained. The cohesive body may also be removed without disturbing the tubing by swabbing or lightening the fluid in the well such as by gas lift, and the like.

10 The present invention will be further described and illustrated by reference to the drawings in which:

Figs. 1 to 3 illustrate a step-wise operation in accordance with the present invention.

15 Referring now to the drawing in which identical numerals will be employed to designate identical parts, numeral 11 designates a well bore drilled from the earth surface 12 to penetrate a plurality of sub-surface earth intervals 13, 14, 15 and 16, among which selected of the intervals may be productive of hydrocarbon and other intervals may be non-productive. For example, intervals 13 and 16 may be productive of hydrocarbon while intervals 14 and 15 may be non-productive. In any event, a casing 17 is arranged in the well bore 11 and is cemented in place employing the usual practice with cement 18 in the well bore 11. The casing 17 has been perforated in the horizon 16 to form perforations 19 through the casing 17, the cement 18 and into the formation material in interval 16. In the practice of the present invention holes or leaks such as 20 may have developed in the tubing 21 and it is desired to repair or replace the tubing 21. The tubing 21 is supported in a well head 22 and in the casing 17 by means of a tubing head and hanger 23. A flange 25 closes the casing-tubing annulus 26 and the tubing 21 extends through the flange 25 and is closed by a valve 26, and is provided with a lateral conduit 27 controlled by valve 28.

20 Since it is desired to repair the tubing 21, the perforations 19 are protected from contact with the fluid which is used to control the well with a protective fluid having the characteristic or property of forming a cohesive mass; the protective fluid is introduced into the tubing through conduit 27 controlled by valve 28 and flowed or pumped downwardly through the tubing 21. The pumping may be conducted by first introducing or pumping the emulsion into the tubing followed by the workover or servicing fluid, which may be oil, fresh or salt water, and the like, into the tubing. As the emulsion flows downwardly through the tubing it may suitably fill the leaks or holes 20 as it issues from the lower open end 29 of the tubing as an elongated body 30 and settles or flows downwardly to fill the casing in the region of the perforations 19. It is to be noted that the elongated body 30 does not intermingle or mix with the well fluids filling the well casing which are displaced up the annulus 26 and from the casing by means of conduit 31 controlled by valve 32.

25 After the cohesive body 30 has filled the casing adjacent the perforations 19 it may be desirable to circulate the well fluids which suitably may contain gas and may be composed of oil, water and gas from the well. This may be done by continuing the pumping of the workover fluids into the tubing through conduit 27 and out through the open end 29 of the tubing. Since the perforations or leaks 20 in the tubing 21 may be filled with the protective fluid the workover fluid flows up the annulus 26 and removes substantially all of the well fluids from the well. Since the workover fluids have sufficient weight to overcome the formation pressure of formation 16, the flange 25 may be unbolted and the leaking tubing 21 may be pulled and replaced with a non-leaking tubing 21a and the Christmas tree replaced such as shown in Fig. 3, the blowout preventers as illustrated by numeral 33 in Fig. 2 having been placed on the head 22 prior to removal of the tubing 21 and hanger 23, if desired. Thereafter the valve 32 remains closed and production is had through the tubing 21a by lightening the column of the workover fluids in the well such as by introducing

a lighter fluid into the well or by swabbing or gas-lift, and the like. The body of protective fluid 30 is displaced up through the open end 29 of the repaired tubing 21a followed by hydrocarbon fluids from the formation 16, it being noted that the perforations 19 have been protected at all times against contact with drilling mud or with workover fluids.

Advantageously, the present invention is applicable to the so-called permanent well completion techniques wherein the tubing is arranged permanently in place once in the economic lifetime of the well and subsequent operations are conducted with the tubing maintained permanently in place. Thus, in accordance with the present invention, by virtue of the property of the protective fluid, it is possible to locate the protective fluid without lowering the tubing and extending the effective length of the tubing by using a tubing extension member. In other words, the protective fluid has sufficient cohesiveness that it resists admixture with well fluids and the like and does not become displaced up the annulus and from the well.

The present invention has been used successfully in several crude oil producing fields. In one operation in the Gulf Coast of Texas it was necessary to repair a leaking tubing, the lower end of which was about 300 feet above the producing interval to be protected. In this operation the protective fluid was poured or pumped into the tubing at the surface following which salt water was pumped downwardly through the tubing until the well fluids in the tubing-casing annulus ceased to contain oil and only salt water was being returned. The protective fluid did not flow up the annulus and was spotted or located in the area in the well from which hydrocarbons had been produced. Thereafter, with the well under control, the well flange was unbolted and the tubing pulled, repaired, and then replaced. The well was then restored to producing hydrocarbons as has been described. In these operations the time involved for removing the well fluids from the well was from about 12 to 18 hours whereas prior to the present invention an amount of time ranging from 48 to 120 hours was required.

Tubing repairs in accordance with the present invention have been performed on several wells with the tubing about 300 feet above the productive zone with success without lowering the tubing or using a tubing extension to place the protective fluid in the desired interval.

In some occasions it may be undesirable or unnecessary to circulate the wells with the workover fluid before removing the tubing for repairs and other operations. Under such conditions the protective fluid is pumped or poured into the tubing and displaced out the bottom of the tubing without any subsequent circulation of the workover fluid. In this manner the protective fluid displaces the well fluids ahead of the protective fluid but yet maintains a sufficiently heavy column of fluid in the well to protect against a blowout when the well is open prior to placement of the repaired tubing and the blowout preventers or conducting of another operation.

Besides the several enumerated advantages of the present invention, the invention is also of utility in that a method is provided wherein loss of salt water, where salt water is the workover fluid, to the formation is prevented.

The present invention, while specifically illustrated with reference to repairing leaking tubing, is applicable to any operations where protective fluid is employed to protect an exposed area or interval following which it is desirable to conduct another operation in the well above the productive interval without moving the tubing. Examples of other operations are installation or repair of gas lift valves, retrievable or otherwise, subsurface pumps, either hydraulic or rod, subsurface chokes, casing leak repairs, replacement of surface control equipment, re-

pair of casing, and replacement of tubing packers, and the like.

It is contemplated that operations as mentioned and described before may be conducted in wells completed in a plurality of zones where the zones are produced simultaneously or selectively either with the fluids from the several zones being commingled or maintained separate from each other. For example, where a well is equipped for dual completion with parallel strings of tubing either concentrically arranged or in side-by-side relationship, it may be desirable to perform an operation as described and, in that event, one or both of the exposed zones may be protected with the protective fluid while the repair or workover operation is carried out without moving the tubing or extending its effective length.

While the invention has been described and illustrated for use in a perforated casing, this is given by way of illustration and not by way of limitation inasmuch as the invention may be practiced in open hole below a cased and tubed well or in a well where a tubing is not used or where a tubing is subsequently run.

Also, while small amounts of the protective fluid in an amount from about 1 to about 20 barrels have been described, lesser or larger amounts may be used. For example, about 200 to 400 barrels of fluids usually fill wells drilled to about 5,000 to about 10,000 feet range depending on the size of the casing. An amount of protective fluid may be used ranging from about 0.5 to 10 percent by volume based on the amount of fluid required to fill the well. Some adjustment in amounts may be desirable where a long exposed area exists in the well.

The nature and objects of the present invention having been completely described and illustrated, what we wish to claim as new and useful and to secure by Letters Patent is:

1. A method for protecting an exposed area in a well having a tubing arranged therein with its lower open end maintained at a level a substantial distance above said area, said well being filled with well fluids, which comprises introducing into said tubing at the well head a stable low fluid loss fluid selected from the group consisting of gels and emulsions of an oily phase and an aqueous phase containing an emulsifying agent, said low fluid loss fluid being free of solids and constituents which might damage said exposed area, having a controllable density by having a weighting agent dissolved in one of said phases, and having a weight at least equal to the weight of a workover fluid for the well and said low fluid loss fluid also having the property of forming a cohesive body, and flowing said low fluid loss fluid out the lower end of said tubing free of any confining channel to form said cohesive body extending in elongated form from said lower end of the tubing through said well fluids 55 separate and distinct from said well fluids to and filling said area, discontinuing introduction of said low fluid loss fluid, and then introducing said workover fluid into said tubing at the well head and flowing said workover fluid out the lower end of said tubing whereby said well fluids are displaced from the well up the annular space between the tubing and the wall of the well, said cohesive body remaining in and protecting said exposed area during displacement of said well fluids while maintaining said tubing with its lower end at said level.

2. A method for protecting an exposed area in a well having a leaking tubing arranged therein with its lower open end maintained at a level a substantial distance above said area, said well being filled with well fluids, which comprises introducing into said tubing at the well head a stable low fluid loss fluid selected from the group consisting of gels and emulsions of an oily phase and an aqueous phase containing an emulsifying agent, said low fluid loss fluid being free of solids and constituents which might damage said exposed area, having a controllable density by having a weighting agent dissolved

in one of said phases, and having a weight at least equal to the weight of a workover fluid for the well and said low fluid loss fluid also having the property of forming a cohesive body, and flowing said low fluid loss fluid out the lower end of said tubing free of any confining channel to form said cohesive body extending in elongated form from said lower end of the tubing through said well fluids separate and distinct from said well fluids to and filling said area, discontinuing introduction of said low fluid loss fluid, then introducing said workover fluid into said tubing at the well head and flowing said workover fluid out the lower end of said tubing whereby said well fluids are displaced from the well up the annular space between the tubing and the wall of the well, said cohesive body remaining in and protecting said exposed area during displacement of said well fluids while maintaining said tubing with its lower end at said level, removing the leaking tubing from the well and replacing same with a tubing free of leaks, removing said cohesive body from said area, and then producing hydrocarbons from said area.

3. A method for protecting an exposed area in a well having a leaking tubing arranged therein with its lower open end maintained at a level a substantial distance above said area, said well being filled with well fluids, which comprises introducing into said tubing at the well head a stable low fluid loss fluid selected from the group consisting of gels and emulsions of an oily phase and an aqueous phase containing an emulsifying agent, said low fluid loss fluid being free of solids and constituents which might damage said exposed area, having a controllable density by having a weighting agent dissolved in one of said phases, and having a weight at least equal to the weight of a workover fluid for the well and said low fluid loss fluid also having the property of forming a cohesive body, and flowing said low fluid loss fluid out the lower end of said tubing free of any confining channel to form said cohesive body extending in elongated form from said lower end of the tubing through said well fluids separate and distinct from said well fluids to and filling said area, discontinuing introduction of said low fluid loss fluid, then introducing said workover fluid free of gas into said tubing at the well head and flowing said workover fluid out the lower end of said tubing whereby said well fluids are displaced from the well up the annular space between the tubing and the wall of the well, said cohesive body remaining in and protecting said exposed area during displacement of said well fluids while maintaining said tubing with its lower end at said level, repairing the leaking tubing, removing said cohesive body from said area, and then producing hydrocarbons from said area.

4. A method for protecting an exposed area in a well having a tubing arranged in a perforated casing with its lower open end maintained at a level a substantial distance above the perforations, said well being filled with well fluids, which comprises introducing into said tubing at the well head a stable low fluid loss fluid selected from the group consisting of gels and emulsions of an oily phase and an aqueous phase containing an emulsifying agent, said low fluid loss fluid being free of solids and constituents which might damage said exposed area, having a controllable density by having a weighting agent dissolved in one of said phases, and having a weight at least equal to the weight of a workover fluid for the well and said low fluid loss fluid also having the property of forming a cohesive body, and flowing said low fluid loss fluid out the lower end of said tubing free of any confining channel to form said cohesive body extending in elongated form from said lower end of the tubing through said well fluids separate and distinct from said well fluids to and filling said casing in the region of the perforations, discontinuing introduction of said low fluid loss fluid, and then introducing said workover fluid into said tubing at the well head and flowing said workover fluid

out the lower end of said tubing whereby said well fluids are displaced from the well up the annular space between the tubing and the wall of the well, said cohesive body remaining in said region and protecting said perforations during displacement of said well fluids while maintaining said tubing with its lower end at said level.

5. A method for protecting an exposed area in a well having a leaking tubing arranged within a perforated casing with its lower open end maintained at a level a substantial distance above said perforations, said well being filled with well fluids containing gas, which comprises introducing into said tubing at the well head a stable low fluid loss emulsion of an oily phase and an aqueous phase containing an emulsifying agent, said emulsion being free of solids and constituents which might damage said exposed area and being of a controllable density by having a weighting agent dissolved in one of the phases of said emulsion and said emulsion also having the property of forming a cohesive body, and flowing said emulsion out the lower end of said tubing free of any confining channel to form said cohesive body extending in elongated form from said lower end of the tubing through said well fluids separate and distinct from said well fluids to and filling said casing in the region of the perforations, discontinuing introduction of said emulsion, then introducing a fluid free of gas into said tubing at the well head and flowing said fluid free of gas out the lower end of said tubing whereby said well fluids are displaced from the well up the annular space between the tubing and the wall of the well, said cohesive body remaining in said region and protecting said perforations during displacement of said well fluids while maintaining said tubing with its lower end at said level, repairing the leaking tubing, removing said cohesive body, and then producing hydrocarbons through said perforations.

6. A method for protecting an exposed area in a well having a tubing arranged therein with its lower open end maintained at a level a substantial distance above said area, said well being filled with well fluids, which comprises introducing into said tubing at the well head a stable low fluid loss emulsion of an oily phase and an aqueous phase containing an emulsifying agent, said emulsion being free of solids and constituents which might damage said exposed area and being of a controllable density by having a weighting agent dissolved in one of the phases of said emulsion and said emulsion also having the property of forming a cohesive body, and flowing said emulsion out the lower end of said tubing free of any confining channel to form said cohesive body extending in elongated form from said lower end of the tubing through said well fluids separate and distinct from said well fluids to and filling said area, discontinuing introduction of said emulsion, and displacing said well fluids from the well up the annular space between the tubing and the wall of the well, said cohesive body remaining in and protecting said exposed area during displacement of said well fluids while maintaining said tubing with its lower end at said level.

7. A method for protecting an exposed area in a well having a leaking tubing arranged therein with its lower open end maintained at a level a substantial distance above said area, said well being filled with well fluids containing gas, which comprises introducing into said tubing at the well head a stable low fluid loss emulsion of an oily phase and an aqueous phase containing an emulsifying agent, said emulsion being free of solids and constituents which might damage said exposed area and being of a controllable density by having a weighting agent dissolved in one of the phases of said emulsion and said emulsion also having the property of forming a cohesive body and flowing said emulsion out the lower end of said tubing free of any confining channel to form said cohesive body extending in elongated form from said lower end of the tubing through said well fluids separate and distinct from

said well fluids to and filling said area, discontinuing introduction of said emulsion, displacing said well fluids from the well up the annular space between the tubing and the wall of the well, said cohesive body remaining in and protecting said exposed area during displacement of said well fluids while maintaining said tubing with its lower end at said level, repairing said leaking tubing, removing said cohesive body, and then producing hydrocarbons from said area.

8. A method for protecting an exposed area in a well having a tubing arranged within a perforated casing with its lower open end maintained at a level a substantial distance above said area, said well being filled with well fluids which comprises introducing into said tubing at the well head a stable low fluid loss fluid selected from the group consisting of gels and emulsions of an oily phase and an aqueous phase containing an emulsifying agent, said low fluid loss fluid being free of solids and constituents which might damage said exposed area, having a controllable density by having a weighting agent dissolved in one of said phases, and having a weight at least equal to the weight of a workover fluid for the well and said low fluid loss fluid also having the property of forming a cohesive body, and flowing said low fluid loss fluid out the lower end of said tubing free of any confining channel to form said cohesive body extending in elongated form from said lower end of the tubing through said well fluids separate and distinct from said well fluids to and filling said area, discontinuing introduction of said low fluid loss fluid, and displacing said well fluids from the well, said cohesive body remaining in and protecting said exposed area during displacement of said well fluids while maintaining said tubing with its lower end at said level.

9. A method for protecting an exposed area in a well having a tubing arranged therein with its lower open end maintained at a level a substantial distance above said area, said well being filled with well fluids, which com-

prises introducing into said tubing at the well head a stable low fluid loss emulsion consisting of an aqueous phase and an oily phase containing a water soluble salt of lignin sulfonic acid emulsifying agent, said low fluid loss emulsion being free of solids and constituents which might damage said exposed area, having a controllable density by having a weighting agent dissolved in one of said phases, and having a weight at least equal to the weight of a workover fluid for the well and said low fluid loss emulsion also having the property of forming a cohesive body, and flowing said low fluid loss emulsion out the lower end of said tubing free of any confining channel to form said cohesive body extending in elongated form from said lower end of the tubing through said well fluids separate and distinct from said well fluids to and filling said area, discontinuing introduction of said low fluid loss emulsion, and then introducing said workover fluid into said tubing at the well head and flowing said workover fluid out the lower end of said tubing whereby said well fluids are displaced, said cohesive body remaining in and protecting said exposed area during displacement of said well fluids while maintaining said tubing with its lower end at said level.

10. A method in accordance with claim 9 in which the oily phase of the emulsion comprises tetrachloroethylene.

11. A method in accordance with claim 10 in which one of the phases of the emulsion contains a corrosion inhibitor.
